[57] CLAIM

The ornamental design for a ball holder, as shown and described.

DESCRIPTION

FIG. 1 is a perspective view of a ball holder, showing our new design;

FIG. 2 is a left side elevational view, the right side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a ball in FIG. 2 is for illustrative purposes only and forms no part of the claimed design.
